UNITED STATES PATENT OFFICE

FRED HIMMEL AND ISIDORE HIMMEL, OF NEW HAVEN, CONNECTICUT, ASSIGNEES TO
THE HIMMEL BROTHERS COMPANY, OF NEW HAVEN, CONNECTICUT, A CORPORATION

STORE-FRONT CONSTRUCTION

Application filed April 2, 1931. Serial No. 527,210.

This invention relates to an improvement in store-front constructions and is similar in operation to the device shown and described in Letters Patent of the United States, No. 1,784,689, granted December 9, 1930, on an application filed by us.

The object is to provide simple means for firmly uniting the inner and outer members for store-front constructions, and the invention consists in the construction as herein-after described and particularly recited in the claims.

In the accompanying drawings:

Fig. 1 is a plan view illustrating a store-front construction embodying our invention, with the front member removed;

Fig. 2 is a front view of the same;

Fig. 3 is an end view of the same;

Fig. 4 is a sectional view taken on the line 20 4-4 of Fig. 2;

Fig. 5 is a sectional view taken on the line 5-5 of Fig. 4;

Fig. 6 is a sectional view taken on the line 6-6 of Fig. 4;

Fig. 7 is a perspective view of the rocker detached; and

Fig. 8 is a perspective view of the coupler detached.

In carrying out our invention, we employ 30 a housing-block 10 similar to that shown in the application, Serial No. 527,209, filed by us in even date herewith, that is, it is provided with trunnions 11 and a shelf 12 on which a sheet of glass 13 may be supported.

Between the trunnions a rocker 14 is pivoted, the inner end of the rocker having a slot 15 to pass on opposite sides of a neck 16 of a screw 17, which is mounted in the housing-block and extends upward through the 40 top of the inner member 18.

Mounted in the outer member 19 is a coupler 20, the upper end extending into a groove 21 at the outer edge of the outer member and its lower end 22 interlocked with the bottom-wall 23 of the outer member. This coupler is formed with an inwardly-extending cam-rib 24 to be engaged by the outer end 25 of the rocker 14 and so that when the inner end of the rocker is forced 50 downward, the coupler will be drawn inward

and force the outer member into engagement with the glass.

These blocks and couplers are located at regularly-spaced intervals in the inner and outer strips and the cam-ribs 24 are so wide 55 that if the couplers and blocks do not exactly align, they will still be in cooperative position, and the top of the rib engaging with the under-side of the shelf 12 prevents the outer member from riding upward and any 60 movement of the rocker necessarily draws the outer member against the glass.

We claim:

1. A store-front construction comprising inner and outer members, a housing-block 65 mounted in the inner member, a screw extending downward through said block, said screw formed with a neck, a rocker pivotally mounted in the housing-block and having one end extending rearward and notched for engagement with the neck of the said screw, and a coupler mounted in the outer member and formed with a forwardly-projecting cam-rib extending into the path of the forward end of the said rocker, whereby the 70 movement of the rocker draws the two said members together.

2. A store-front construction comprising inner and outer members, a housing-block fixed in position in the inner member, said 80 housing-block formed with forwardly-projecting trunnions and a forwardly-projecting shelf, a rocker pivotally connected with said trunnions and formed at its inner end with a notch, a screw vertically movable in the mounting-block and coupled with the notched inner end of the rocker, and a coupler fixed in the outer member and formed with a forwardly-projecting cam-rib engaging the underside of said shelf, the under-face of the 85 rib extending over and in engagement with the forward end of the rocker.

In testimony whereof, we have signed this specification.

FRED HIMMEL.
ISIDORE HIMMEL.
